LIMITED, OF HAMILTON, ONTARIO, CANADA

TWO-CYCLE ENGINE

Application filed February 21, 1929. Serial No. 341,728.

The principal objects of this invention are, to increase the efficiency of the two cycle type of internal combustion engine by effecting a thorough scavenging of the cylinders and ensuring a complete charge of carbureted air.

The principal features of the invention consist in the arrangement of a valving element supported by each of the pistons in a pair of cylinders connected by a common combustion head, said valving elements being operated by the transverse swinging movement of the connecting rod or crank.

In the drawing, Figure 1 is a longitudinal midsectional view of a pair of cylinders of an engine constructed in accordance with this invention.

Figure 2 is a cross sectional view on the line 2—2 of Figure 1.

Figure 3 is a cross sectional view on the line 3—3 of Figure 1.

In the operation of two cycle combustion engines there has been an existent fault which many have endeavored to overcome, namely, the difficulty of expulsion of the products of combustion which causes the following charge of combustible fluid to be less effective than that in a four cycle engine.

It has been proposed to increase the efficiency of the two cycle engine by arranging the cylinders in pairs with one piston operating slightly in advance of the other in order to open the exhaust port prior to the opening of the intake and it has also been proposed to combine with the piston of a two cycle engine a valving element operated by the crank movement and it is the purpose of this invention to so combine these features as to produce a further improvement in the operation.

In the construction herein shown the cylinders 1 and 2 are connected at their outer ends by a common combustion chamber 3.

The cylinder 1 is provided with an exhaust port 4 arranged intermediate of its length and a cylinder 2 is provided with an intake port 5 arranged intermediate of its length.

Pistons 6 and 7 are arranged in the cylinders 1 and 2 respectively and each of these pistons is provided with a valving element here shown in the form of sleeves 8 and 9

which encircle the pistons with a snug sliding fit and said sleeves engage the cylinder walls in a piston fit.

A sleeve 8 is provided with a port 10 which is adapted to co-operate with the exhaust port 4 in the cylinder 1 and the sleeve 9 is provided with a port 11 adapted to co-operate with the intake port 5 of the cylinder 2.

Each of the valving elements is provided with a lug extension 12 which is operatively engaged by an arm 13 extending from the connecting rod 14 in the direction of the swinging movement of said rod.

It will be understood that as the crank shaft revolves it reaches a point in its downward throw where there is very little downward movement of the piston but in such position of the crank the continued movement swings the connecting rod through a considerable arc while the piston is practically stationary.

The piston sleeves are so arranged on the pistons that when the main crank 15 swings in its downward travel the pistons move below the port openings in the cylinder, while the sleeves carried by said pistons still retain the ports closed.

The transverse swinging of the connecting rod, which produces very little longitudinal movement of the piston in the cylinder does however operate the extension arm 13 engaging the lug 12 to move the sleeve very rapidly.

The ports in the sleeve 8 are arranged to open the exhaust port 4 in advance of the opening of the intake 5.

The ports 11 in the sleeve 9 are so arranged that the intake port 5 is retained closed although the top of the piston has moved below the intake port and the continued downward movement of the piston brings the ports 11 into alignment with the intake port 5 following the opening of the exhaust port in the other cylinder.

The combustible gases are fed to the cylinders under pressure and flow into the cylinder 2 at the bottom end, forcing the burnt gases upwardly and through the common combustion head 3 to the cylinder 1 from the bottom of which said gases are exhausted.

The following of the burnt gases in this

manner ensures a thorough scavenging of the cylinders.

The downward movement of the sleeve 8 in the opening of the exhaust port eventually moves the sleeve ports to be closed by the piston and the return upward movement of the piston closes the exhaust port prior to the closing of the intake, consequently the forced charge of carbureted air continues to flow into the inlet cylinder after the exhaust has been closed.

This arrangement results in the maximum volume of carbureted air being forced into the cylinders.

15 It will be seen that with the cylinders arranged in pairs with their centers in the plane of the crank shaft any desirable number of pairs of cylinders may be grouped in radial arrangement around the crank shaft.

20 This type of engine described may be operated through the injection of carbureted air, or it may be operated by admitting air to the cylinders under pressure with a fuel introduced in fluid form on solid injection.

25 What we claim as our invention is:—

1. In a two cycle multiple power cylinder engine having a crank shaft provided with a pair of cranks one in advance of the other, a pair of cylinders aligned with the crank shaft and connected at the outer ends by a common combustion chamber, one of said cylinders having an exhaust port and the other of said cylinders having an intake port, connecting rods and pistons operatively connected with said crank shafts and positioned thereby one in advance of the other, a sleeve surrounding each of said pistons, each having ports therein adapted to co-operate with the port of the respective cylinder, and means operated from the respective connecting rods for operating said sleeves whereby the advance movement of the connecting rod in the exhaust cylinder is utilized to close said exhaust port prior to the closing of the inlet port by the movement of the other connecting rod.

2. In a two-cycle engine, the combination of paired power cylinders aligned with the crank shaft one of said cylinders having an inlet port and the other cylinder having an exhaust port, said cylinders having a common combustion head permanently connecting same and pistons arranged therein and operating one in advance of the other, means operable with said pistons and movable in relation thereto for respectively controlling the exhaust and inlet of said cylinders, and operating members connected with the connecting rods of said pistons at a point below their pivotal connection therewith and extending in planes parallel to the planes of reciprocation of the connecting rods and operatively connected with said movable means whereby the advanced movement of one connecting rod over the other is utilized to im-

part an advanced positioning to the respective operable control means relative to the other.

3. In a two cycle engine the combination of paired cylinders aligned with the crank shaft having a common combustion head and pistons arranged therein and operating one in advance of the other, sleeves in said cylinders for controlling the inlet and exhaust thereof, said sleeves having sockets in alignment with the plane of reciprocation of the respective connecting rods and operating members connected with the connecting rods of said pistons and extending in planes parallel to the planes of reciprocation of the latter and engaging the wall of the sockets of the sleeves in operating contact.

4. In a two cycle engine the combination of paired cylinders aligned with the crank shaft having a common combustion head and pistons arranged therein and operating one in advance of the other, means operable with said pistons and movable in relation thereto for controlling the exhaust and inlet of said cylinders, said means being formed with sockets and rigid studs extending transversely from the connecting rods in the plane of reciprocation of the latter, said studs having their outer ends rounded and extending into the respective sockets of said operable means for actuating the same.

5. In a two-cycle multiple cylinder engine, the combination of paired power cylinders aligned with the crank shaft, one of said cylinders having an inlet port and the other cylinder having an exhaust port, said cylinders having a common combustion head permanently connecting same and pistons arranged therein and operating one in advance of the other, means operable with said pistons and movable in relation thereto for respectively controlling said exhaust and inlet of said cylinders, and means operatively connecting the connecting rods of said pistons with said respective operable controlling means for actuating the same whereby the lead of one connecting rod over the other effects the advance movement of the respective controlling means relative to the other to close the exhaust port of the one cylinder prior to the closing of the inlet of the other cylinder.
